CLAIM

The ornamental design for a handle for portable computer, as shown and described.

DESCRIPTION

FIG. 1 is a front and top perspective view of a handle for portable computer showing our new design;

FIG. 2 is a front and bottom perspective view thereof;

FIG. 3 is a rear and top perspective view thereof;

FIG. 4 is a rear and bottom perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is a cross-sectional view taken along lines 11-11 of

FIG. 5, wherein internal structures are omitted; and,

FIG. 12 is a front elevational view thereof shown with environmental features for illustrative purposes.

Broken lines depicting a portable computer in FIG. 12 represent unclaimed environment and form no part of the claimed design. All other broken lines in the drawings illustrate portions of the handle for portable computer that form no part of the claimed design.

1 Claim, 12 Drawing Sheets
